Primary Examiner — Angela J Lee*Assistant Examiner* — Rebekah A Caruso(74) *Attorney, Agent, or Firm* — Knobbe, Martens, Olson & Bear, LLP(57) **CLAIM**

The ornamental design for a telematics device, as shown and described.

DESCRIPTION

FIG. 1 is a front, left, top perspective view of a telematics device, showing my new design;

FIG. 2 is a front view thereof;

FIG. 3 is a right side view thereof;

FIG. 4 is a back view thereof, wherein the back view comprises a mini-USB socket cover and inset sockets for Molex Micro-Fit connectors (4-pin, 12-pin, and 10-pin, from left to right);

FIG. 5 is a left side view thereof;

FIG. 6 is a top view of thereof; and,

FIG. 7 is a bottom view thereof.

Broken lines are used in the drawings to depict portions of the telematics device that form no part of the claimed design.

1 Claim, 7 Drawing Sheets(56)
